UNITED STATES PATENT OFFICE.

THEODOR REUTER, OF WINTERTHUR, SWITZERLAND.

INTERNAL-COMBUSTION ENGINE.

971,793.

Specification of Letters Patent.

Patented Oct. 4, 1910.

Application filed August 13, 1909. Serial No. 512,697.

To all whom it may concern:

Be it known that I, THEODOR REUTER, engineer, a citizen of the Swiss Republic, residing at 24 Obere Wielandstrasse, Winterthur, Switzerland, have invented certain new and useful Improvements in Internal-Combustion Engines; and I do hereby declare the following to be a full, clear, and exact description of the invention, such as will 5 enable others skilled in the art to which it appertains to make and use the same.

The object of the present invention is to prevent accidental admission through the starting valve of an internal combustion engine of the air or gas under pressure which is to be used for starting the engine.

Hitherto the starting valve has usually opened inward into the combustion chamber or the cylinder, so that the valve has 20 been held closed by the pressure in the cylinder. In this case, if the pressure of the air for starting is very great, the valve may be opened by this pressure and the air be admitted to the cylinder; this might also happen if the valve spring failed to act. Should such an accidental inflow occur before or after the exhaust valve closed, that is, before or during compression, the pressure in the working cylinder may rise so high as to injure the engine or even to prove dangerous.

In reversible combustion engines, the starting valve must not admit any air under pressure to the working cylinder when the reversing mechanism is being turned back 35 through the starting position, as when it is being turned from the position which it has when the engine is running to that which it has when the engine is at rest. This is of especial importance because it may happen 40 that during this movement of the reversing mechanism the starting valve is opened, which would hinder the engine from coming to rest. For the purpose of removing this difficulty and danger the present invention 45 provides a cut-off device such as a check valve in the pipe conducting the compressed-air to the starting valve, which device is opened to allow passage of the air, by the act of reversing the engine, but otherwise cuts 50 off the air from the starting valve.

The invention attains two ends:—During running, when the starting valve is not to be operated, the supply of air to this valve is automatically cut off by the check valve. 55 When the reversing mechanism is turned from the running position to the stationary

position, the check valve prevents compressed air from entering the cylinder, particularly at the period when the reversing mechanism passes through the starting position.

In the accompanying drawing, Figure 1 is a sectional view of mechanism embodying the invention, and Fig. 2 is a detail of the same.

The starting valve *a* is controlled from the shaft *b* by the oscillating cam *c* adapted to be adjusted on the shaft by the reversing shaft *d* through the lever *m* and connecting rod *m'*. In the median or intermediate position the cam had no action on the starting valve, while in its extreme positions it opens the valve for starting the forward and backward running respectively. The reversing shaft *d* is set to the various positions for 70 stationary starting and running by means of the hand lever *n*. The compressed air for starting flows to the starting valve through the casing *e* of the check valve *f*, which remains closed by the pressure of the 75 air behind it. This check valve is opened by the action of the cam *h* secured on the reversing shaft *d*; the cam operates on a releasing mechanism *g* and *h*, through roller *i*.

The releasing mechanism comprises a 80 guide rod *h* which effects the release and has a groove along one side, and a two armed lever *g*, which by the action of plate springs *l'* on the pawl *l* journaled on the lever *g*, is held in a position in which the check 85 valve *f* is closed. The pawl *l* is enabled to hold the lever in this position since it is held against a support on the stationary valve casing by means of the above mentioned springs *l'*, so that on any movement of the 90 lever *g* out of the position shown, a turning movement is exerted on the lever *g* which tends to return it to its normal position. If, for reversing or starting, the cam disk *k* is rotated, valve *f* is lifted by the spring pawl 100 lever *g*, and air under pressure is free to pass to the starting valve *a*, which is controlled according to the direction of running of the starting to the running position, the simultaneous continued rotation of the cam 105 disk *k* depresses the rod *h* so far that the left hand pawl of the lever *g* slips into the notch in the rod *h*, whereupon the lever *g* springs back to its original position through the pawl *l*, and the valve *f* which is now out 110 of contact with the right hand pawl of the lever *g* is closed by its spring. The supply

of compressed air to the starting valve is thus cut off. On returning the reversing mechanism from the running position, the left-hand pawl of lever *g* does not again engage with the guide rod *h* until the reversing mechanism is in the stationary position. Thus the valve *f* remains closed so that no compressed air can pass to the starting valve. The check valve is therefore only opened when compressed air is to enter the cylinder through the starting valve.

Without limiting myself to the construction shown, I claim:—

1. The combination with a starting valve of an internal combustion engine, and compressed air piping leading to the same, of a cut-off valve in said piping, reversing mechanism for the engine, and an operating connection between said mechanism and said valve which permits the valve to stay closed during the operation of the engine and during the movement of the reversing mechanism from running position to stationary position.
2. The combination with a starting valve of an internal combustion engine, of a cut-off valve in connection therewith, controlling mechanism having a working position, a stop position, and a starting position intermediate the working and stop positions, and an operative connection between said mechanism and said cut-off valve which keeps the latter closed during the movement of the

controlling mechanism from the working to the stationary position.

3. The combination with a starting valve of an internal combustion engine, and compressed air piping leading thereto, of a cut-off valve in said piping, a reversing shaft having a cam, and means to transmit the movements of said cam to said cut-off valve.

4. The combination with a starting valve of an internal combustion engine, of a cut-off valve in connection therewith, a reversing shaft, a cam on the reversing shaft, and means to transmit the movements of said cam to the cut-off valve, including a sliding spring-pressed member resting against the cam, and releasing mechanism in connection with said member and in operative relation with the spindle of said cut-off valve.

5. The combination with a starting valve of an internal combustion engine, of a cut-off valve in connection therewith, a countershaft having a cam to actuate the starting valve, a reversing shaft having a cam operatively connected with the cut-off valve, and an operative connection between the countershaft cam and the reversing shaft.

In testimony whereof I have affixed my signature, in presence of two witnesses.

THEODOR REUTER.
